UNITED STATES PATENT OFFICE.

RICHARD WEBB BURNETT, OF MONTREAL, QUEBEC, CANADA.

GRAIN-DOOR.

1,069,672.

Specification of Letters Patent.

Patented Aug. 12, 1913.

Application filed December 14, 1910. Serial No. 597,181.

To all whom it may concern:

Be it known that I, RICHARD WEBB BURNETT, a citizen of the United States of America, residing at No. 42 The Linton, 5 Montreal, Quebec, Canada, have invented new and useful Improvements in Grain-Doors, of which the following is a specification.

My invention relates to grain doors and 10 has for its object to provide a door that will prevent leakage when closed but which can be readily opened to empty the car.

Hitherto it has been found that with ordinary hinges or hanging supports the grain 15 pressure is so great that the door has become jammed and great difficulty has been experienced in opening the door. My invention is designed to overcome this difficulty.

Reference is made to the annexed drawings in which—

Figure 1. shows a perspective view of the door from the inside of car. Fig. 2. shows the upper end of hinge. Fig. 3. shows the lower end of hinge. Fig. 4. shows the closing edge of door, viewed from the outside.

The door A. consists preferably of a corrugated sheet with flat edges. On one of these edges two half round bars are riveted and with extensions of the bar E. above E³ 30 and below E⁴. form the pivoting portion of the door. Let into the edge of the door post B. is a quarter circle groove B¹. suitably faced with metal B². which forms the seat of the bar E. A cap F¹. let into the car 35 floor F. accommodates the lower end E⁴ of the bar E. The loop B⁴. retains the upper end E³ of the bar E in the groove B¹. On the opposite edge of the door two or more lugs A¹. A². extend outwardly. The door 40 post C. is provided with projections C¹. C². on which the lugs bear when the door is closed. Near the edge of the door A. on which the lugs A¹. A². are, is a hinged flap D. which extends beyond the lugs A¹. A². 45 and bears on the door post C. when the door A. is closed.

In its normal position the door A. rests on the car floor F. Its lower edge forms a sealed contact with the floor. The bar E, 50 fitting accurately in the groove B¹, provides

a sealed hinge while the flap D, covering the opposite edge of the door A, and the lugs A¹. A². prevents leakage at that point.

The bar E, is adapted to have a limited vertical sliding movement in the groove B¹, 55 when the door A, is raised vertically. The lugs and projections are so proportioned that the lugs are freed when the door is raised a short distance.

The operation is as follows:—When the 60 car is filled with grain the door is held firmly in position. In order to open it the operator prys up the door from the outside. The bar slides up in its groove and the lugs slide upward on the projections of the door 65 post. When the lugs reach the spaces the door swings open, outwardly.

It is obvious that the door may be swung inwardly into the car; also, that when the door is swung outwardly the flap D will 70 swing inwardly automatically due to its engaging the lugs A¹. A².

Having now described my invention and its method of operation, what I claim and desire to secure by Letters Patent is:—

1. In a device of the character described, a grain car door hinged to the door frame and being mounted for vertical movement, a projection on the door, a projection on the door frame, a flap hinged to the door and overlapping said projections, said projections being normally engaged and being adapted to disengage when the door is moved vertically.

2. In a device of the character described, 85 a grain car door hinged to the door frame and being mounted for vertical movement, a projection on the door, a projection on the door frame, said projections being engaged when the door is resting on the 90 door sill and disengaged when the door is raised off the door sill, a flap secured to the door and normally overlapping the said projections, said flap being mounted to move to permit unobstructed swing of 95 the door when the projections are disengaged.

3. In a device of the character described, 100 a grain car door, means permitting the door to slide vertically, means permitting the

door to swing on either side of the door frame, projections on the door and door frame normally engaged and adapted to be disengaged upon the door being moved vertically, and a flap on the door mounted so as to be moved to permit said swinging of the door.

Signed at Montreal this seventeenth day of November, 1910, in the presence of two witnesses.

RICHARD WEBB BURNETT.
